CLAIM

The ornamental design for a passenger sleeper cabin, as shown and described.

DESCRIPTION

FIG. 1 is a front perspective view of a passenger sleeper cabin showing my new design, and showing the stairwells at the ends of the cabin in phantom;

FIG. 2 is a top plan view of the passenger sleeper cabin of FIG. 1;

FIG. 3 is a front elevational view of the passenger sleeper cabin of FIG. 2;

FIG. 4 is a side elevational view of the passenger sleeper cabin of FIG. 3; and,

FIG. 5 is an enlarged perspective view of a portion of the passenger sleeper cabin of FIG. 1.

The broken lines represent unclaimed portions of the passenger sleeper cabin and form no part of the claimed design.
